UNITED STATES PATENT OFFICE.

SIMON KOIRANSKY, OF LYON, FRANCE.

APPARATUS FOR SEA NAVIGATION.

1,344,903.

Specification of Letters Patent. Patented June 29, 1920.

Application filed May 16, 1918. Serial No. 234,905.

To all whom it may concern:

Be it known that I, SIMON KOIRANSKY, citizen of the Republic of Russia, residing at 19 Cours La Fayette, Lyon, Rhone, in the

5 Republic of France, have invented new and useful Improvements in Apparatus for Sea Navigation, of which the following is a specification.

The object of the present invention is a 10 floating apparatus the essential feature of which is an arrangement which reduces to a minimum the action of waves detrimental to the displacement of ordinary ships, and even transforming this detrimental effect 15 into an action which is useful to floating capacities. This system can be applied to any means of propulsion, paddle wheels, naval propellers, aerial propellers, sails, etc.

The detrimental effects of the waves are 20 of the static and dynamic order.

Those of the first kind give to the ships oscillating movements known under the names of rolling or pitching.

Those of the second kind give cause to in- 25 stability, to jerks and to variability of translation speed which are harmful to the ship, to the engines and to the crews and reduce the output of the whole.

To obviate these inconveniences, in the 30 apparatus hereinafter described, the principal matters to be transported and which habitually are composed of the usual lead-burden (crew-stores-cargo), the machinery and the structure which carries them are, 35 by construction, isolated from the agitated surface of the water, above which they are held by the action of the several deformable articulated devices which rest on floats proper.

40 The deformations of the articulated systems are such that they allow the main masses to follow a course in a substantially fixed horizontal plane whatever may be the height and the direction of the waves on 45 which the floats are passing.

In the annexed drawing, given as an example:

Figures 1, 2 and 3 are diagrams illustrating respectively an end view, a plan view 50 and a side elevation view of an apparatus according to the invention.

Figs. 4 and 5 are diagrams, respectively of an end view and a plan view, showing a modified construction of this invention.

55 Fig. 6 is a plan view of still another form of construction of the apparatus.

Figs. 7 and 8 show detailed diagrams in front elevation and in plan of a device according to the invention provided with the floats.

Fig. 9 shows a modified form of construction of the apparatus shown in Figs. 7 and 8.

Fig. 10 is a similar diagram to Fig. 7 and refers to a modification in construction.

Fig. 11 shows a diagrammatic front elevation view of an apparatus according to the invention, this view being intended to show the controlling means.

Referring to Figs. 1, 2 and 3, one sees that 70 the apparatus consists essentially of a central body *a* supported by floats *b* through the medium of articulated systems *c*.

The central body *a* is constituted by a hollow beam which can be of any suitable shape 75 and section and which can be built up of wood, metal, cement or any other suitable material. This hollow beam carries the useful load, the engines, the crew and carries the sails in the case of propulsion by wind 80 power.

The floats can be of any number, varying according to the size and the power of the apparatus. The apparatus can be fitted not only with up-lifting, even sized, floats as 85 shown at *b* in Figs. 1, 2 and 3, but also be fitted with up-lifting floats *b'* and stability floats *d* (Figs. 4 and 5), the up-lifting power of the latter being the same for all the floats *d* but being different to that of the 90 floats *b'*. In the case of the floats *b* (Figs. 1, 2 and 3) and the floats *d* (Figs. 4 and 5) the plan of useful vertical elastic deformations *i. e.* the plan of the deformations of the articulated systems *c* is always perpendicular to the direction of travel *X—X*, as 95 shown in *Y—Y*.

For the floats *b'*, the plan *Z—Z* of elastic deformations is parallel to the direction of travel *X—X*.

The plan of elastic deformations of the articulated systems corresponding to the floats *b* can also be in oblique with relation to direction of travel, as shown in *Y'—Y'* in Fig. 6.

100 The detail of the articulated systems *c* interposed between the beam *a* and the floats *b*, *b'* and *d* is given in Figs. 7 and 8. The beam *a* is fitted with a bearing *e* in which can oscillate an axle carried by the side 110 lever *f*. This side lever carries at its lower end a joint *g* in which passes a vertical shaft

h guided by the float *b*. The upper end of the lever is connected by a rod *i* to any suitable kind of elastic damper *j*, made for instance of a piston moving in the body of a pump containing a fluid under pressure (Figs. 7 and 8) or by an india rubber stretcher or, again, by a spring as shown in Fig. 10.

On smooth water, the damper *j* maintains the float in its lowest position with relation to the beam *a*. The pressure of a wave, increasing the supporting power of the float, raises it by compressing the damper by the side lever *f* and the connecting rod *i* as shown by the dotted lines in Fig. 7. The excess of pressure of water is thus prevented from being transmitted to the beam *a* and thereby affect the stability of this beam.

The upper end of the vertical shaft *h* passes through a joint *k* carried at the end of a connecting rod *l*, pivoted in *m* to the beam *a*. The joints *e*, *g*, *k* and *m* are disposed as a parallelogram. It results therefrom that during the deformations of the apparatus, the shaft *h* remains in a plan parallel to the symmetric plan of the apparatus and the float *b* remains horizontal in its longitudinal direction and bears on the water by only one suitable surface *n* whatever may be the deformations. The rotations of the shaft *h* in the joints *k* and *g* allow the floats *b* to avoid the side jerk of an oblique swell with relation to the direction of travel X—X of the apparatus in automatically deviating as shown by dotted lines in Fig. 8 according to the direction of the component of the relative speeds of the apparatus and of the swell, which presents the minimum of resistance to the forward movement. The summits *k* and *g* of the articulated system constituted by the side lever *f* are conveniently held by stays *o* to prevent detrimental displacements with relation to the beam.

45 It will be noted that the damper or shock absorbing member *j* acts upon the lever *f* with a comparatively short leverage while the float may act upon the lever with a greater leverage. By this means, the floats 50 may be mounted to have a relative vertical displacement corresponding to the whole height of the waves without unduly increasing the dimensions of the shock absorbers which oppose said displacement.

55 Fig. 9 shows a modification of the system of mounting up the vertical shaft on the float *b* and on its joints *g*, *k*. This shaft *s* is mounted so as to be capable of oscillating only in a vertical plane on the joints *g*, *k* 60 and can not rotate about its axis. According to this construction the float is movable about the vertical shaft *s* which is mounted on said float by the medium of ordinary bearings *u*, *t* and a step bearing *v* fixed to 65 the float.

The deformable system which is held between beam *a* and the float *b* can, besides, be built in a more simple manner as shown for example in Fig. 10, but it has then fewer qualities. One sees in this diagram that it 70 can be composed simply of a side lever *f*, a damper *j* and a float *b*.

The direction of the apparatus can be obtained by interior rudders *p* (Fig. 11) disposed on rear floats and resisting to their 75 forward movement. These rudders are movable about axles *q* which are oblique with relation to a longitudinal plane of symmetry of the apparatus so that the rotation of one rudder entails at the same time its 80 immersion. For instance, these rudders can be controlled by levers pulled by cables which lead to the control station placed in beam *a* and going along the side levers *f*.

It will further be noticed that to the floats 85 can be added leeway keels *r*.

The arrangements described have been given as examples and they can be modified in their details according to constructive conveniences without departing from the 90 spirit of the invention.

Having now described my invention, what I claim as new and desire to secure by Letters Patent is:

1. An apparatus for sea navigation comprising in combination a superstructure, floats, pivotally mounted levers connecting the floats to the superstructure and shock absorbing members mounted on the superstructure and engaging with the levers, the 100 shock absorbing members being adapted to act upon the levers with a leverage shorter than that of the floats.

2. An apparatus for sea navigation comprising in combination a central body, supporting floats, stability floats, articulated devices connected to the central body and to the supporting and stability floats respectively, substantially as described and for the 110 purpose set forth.

3. An apparatus for sea navigation comprising in combination, a central body, floats adapted to support said body, articulated devices perpendicular to the direction of travel of the apparatus and connected to 115 the central body and to the float, substantially as described and for the purpose set forth.

4. An apparatus for sea navigation comprising, in combination a superstructure, 120 floats, pivotally mounted levers connecting the floats to the superstructure and means whereby the floats can be displaced with respect to the superstructure while remaining horizontal in their longitudinal direction. 125

5. An apparatus for sea navigation comprising in combination a central body, floats adapted to support said body, levers pivoted on the central body, dampers fixed on said body and connected to the inner ends of the 130

levers and vertical shafts fixed to the floats and pivoted on the outer ends of the levers, substantially as described and for the purpose set forth.

5 6. An apparatus for sea navigation comprising in combination a central body, floats adapted to support said body, levers pivoted on the central body, dampers fixed on said body and connected to the inner ends of the 10 levers, vertical shafts fixed upon the floats respectively and pivoted on the outer ends of the levers and connecting rods pivoted at their inner ends to the central body and by their outer ends to the tops of the vertical 15 shafts so as to form with the said levers articulated parallelograms, substantially as described and for the purpose set forth.

7. An apparatus for sea navigation comprising in combination a central body, floats 20 adapted to support said body, levers pivoted on the central body, dampers fixed on said body and connected to the inner ends of the levers, vertical shafts mounted upon the floats, bearings fixed to said floats and in 25 which are mounted the vertical shafts so

that the floats can rotate about said shafts, connecting rods pivoted at their inner ends to the central body and joints provided at the outer ends of the levers and of the connecting rods in which are pivoted the vertical shafts so as to be capable of oscillating only in a vertical plane, substantially as described and for the purpose set forth. 30

8. An apparatus for sea navigation comprising in combination a central body, front 35 and rear floats adapted to support said body, articulated devices connected to the central body and to the floats, and internal rudders arranged on the rear floats and movable about axes which are oblique with relation 40 to the longitudinal plane of symmetry of the apparatus, substantially as described and for the purpose set forth.

In testimony whereof I have signed my name to this specification in the presence of 45 two subscribing witnesses.

SIMON KOIRANSKY.
